UNITED STATES PATENT OFFICE.

PEREZ M. STEWART, OF NEW YORK, N. Y., ASSIGNOR, BY MESNE ASSIGNMENTS, TO
ASBESTOS PROTECTED METAL CO., A CORPORATION OF MASSACHUSETTS.

BUILDING CONSTRUCTION.

1,073,542.

Specification of Letters Patent. Patented Sept. 16, 1913.

Application filed November 3, 1912. Serial No. 729,574.

To all whom it may concern:

Be it known that I, PEREZ M. STEWART, a citizen of the United States, and a resident of the borough of Manhattan, in the city, county, and State of New York, have invented an Improvement in Building Construction, of which the following description, in connection with the accompanying drawings, is a specification, like characters 10 on the drawings representing like parts.

This invention relates to a composite building structure especially designed and adapted among other uses to be employed as the roof, walls and floors of mills and 15 other buildings.

The invention has for its object to provide a reinforced concrete construction which is simple, inexpensive, durable and highly efficient.

20 The invention is herein shown as embodied in a roof to which it is particularly applicable. To this end, the roof is provided with a corrugated member, preferably a sheet of metal and preferably corrugated asbestos protected metal, said member being composed of a plurality of corrugated sheets which are secured to the roof purlins in a 25 novel manner as will be described. The concrete is laid upon the corrugated member and is provided with a metal reinforcement, which is mechanically bonded to the roof purlin as will be described. Provision is also made for supporting the metal reinforcement above the roof purlins as will 30 be described.

These and other features of this invention will be pointed out in the claims at the end of this specification.

Figure 1 represents a sufficient portion of 40 a roof construction embodying this invention to enable it to be understood. Fig. 2, a section on an enlarged scale on the line 2—2 Fig. 1. Fig. 3, a section on the line 45 3—3 Fig. 1, with the concrete in position. Fig. 4, a detail of the bridge or support for the metal reinforcement, and Figs. 5 and 6, details to be referred to.

Referring to the drawing, *a*, *b*, represent 50 two adjacent sheets of corrugated material, preferably asbestos protected metal, which form part of the corrugated member of the roof construction. The sheets *a*, *b*, have their adjacent ends overlapped and sup-

ported by a metal roof purlin *c*, of known construction and usually a channel iron having a flange *d* at its upper end, which is engaged on its upper and lower surfaces by a purlin clip *e*, whose substantially flat upper part or member has secured to it a rivet *f*, preferably a self punching rivet, 60 which is pointed at its upper end and is designed to be forced through the overlapping portions of the sheets *a*, *b*, by striking the latter on their upper surfaces with a suitable tool. After the sheets *a*, *b*, have 65 been penetrated by the rivet *f*, a bridge piece or support *g* having a base flange 10 provided with a hole 12 is placed over the rivet *f*, and the upper end of the latter is then headed as represented in Fig. 2 to 70 firmly secure together the bridge piece *g* and the overlapping ends of the corrugated sheets *a*, *b*, and through the purlin clip to firmly secure the said sheets to the roof purlin. The base flange 10 of the bridge 75 piece serves as a washer against which the head of the rivet bears. The bridge piece thus has its lower portion located within a valley 14 of the corrugated sheet and is provided with an upright portion or member, which is made of sufficient length to extend above the highest part of the corrugated sheets, and is slotted at its upper end 80 to form fingers 15, 16, one of which is 16, is bent at an angle to the other to form a 85 V or crotch for the reception of a reinforcing rod 17, which extends longitudinally of the corrugated sheets, and which serves to bind or secure a transverse reinforcing rod 18 in the slot 19 formed in the upper end 90 of the bridge between the fingers as clearly represented in Figs. 1, 2 and 4. The longitudinal reinforcing rods 17 are inclined down from the bridge toward the corrugated sheet and are held in the valley by retaining clips 20, which hook over the rod 17, and have a base flange 21 which is bolted, riveted or otherwise secured to the corrugated sheet.

The bridge pieces *g* may be located in 100 each valley of the corrugated sheet but by means of the cross rod 18 supported by the bridge pieces, the latter can be separated by one or more valleys, as the cross rod serves as an elevated support for the tension rods 17 105 of the intermediate valleys as clearly shown.

in Fig. 1, which serves to reduce the cost of construction. The tension rods 17 located in the plane of the valleys may be connected together between the bridge pieces in the same valley by cross wires 25, which may be twisted around the tension rods as shown in Fig. 1 to mechanically connect the longitudinal and transverse rods of the metal reinforcement. After the metal reinforcement has been secured in place on the corrugated sheets, in which it is held in fixed position by the retaining clips 20, the concrete 26 is laid thereon to the desired thickness and when set, said concrete layer may have applied to it a protective layer 27 of any suitable material such as asphalt and gravel.

I have herein represented the invention as embodied in the roof of a building, but it is not desired to limit the invention in this respect as the same construction may be used for the walls and floors of the building.

Claims.

1. In a building construction, in combination, roof purlins, corrugated metal sheets supported by said purlins and having their adjacent ends overlapped above a purlin, a clip engaging said purlin and having a self penetrating rivet extended through the overlapped portions of said metal sheets, a bridge piece secured to said metal sheets by said rivet, tension rods supported by said bridge piece, a cross rod supported by said bridge piece and retained thereon by said tension rod, metal clips secured to the bottom of the valleys of the corrugated metal sheets and engaging said tension rods, and a layer of concrete laid upon said corrugated metal sheets and embedding said tension rods, bridge pieces and cross rods, substantially as described.

2. In a building construction, in combination, roof purlins, corrugated metal sheets supported by said purlins and having their adjacent ends overlapped above a purlin, a clip engaging said purlin and having a member resting on the upper surface thereof, and a rivet extended through the said member and provided with a pointed free end extended through the overlapping sheets to enable the said sheets to be perforated on the job by said rivet and secured to said purlin, substantially as described.

3. In a building construction, in combination, roof purlins, corrugated sheets supported by said purlins, a clip engaging said purlin, a bridge piece secured to said purlin clip, a tension rod supported by said bridge piece above the corrugated sheet and inclined downwardly toward said sheet above a valley thereof, and a retaining clip located in said valley and engaging said tension rod, substantially as described.

4. In a building construction, in combination, a corrugated sheet, a support for the

same, a metal reinforcement comprising rods extended longitudinally of the corrugated sheet above the valleys thereof and rods extended transversely of said corrugated sheets, bridge pieces located in valleys of said corrugated sheet and supporting the said rods, and means located in the valleys of said corrugated sheets and engaging said longitudinal rods to retain them in fixed position, substantially as described.

5. In a building construction, in combination, a corrugated sheet, a bridge piece riveted thereto in a valley thereof and having its upper end extended above the corrugated sheet and provided with fingers, one of which is bent at an angle to the other, a reinforcing rod extended between the said fingers transversely of the corrugated sheet, and a second rod extended between the fingers longitudinally of the corrugated sheet, substantially as described.

6. In a building construction, in combination, a corrugated sheet, a metal reinforcement having rods extended longitudinally of the said sheet above the valleys therein and additional rods extended transversely of the said sheet and secured to the first mentioned rods, means located in the valleys of said sheet to support said rods above the latter, and means in the said valleys to engage said rods and retain them in fixed position with relation to said corrugated sheet, substantially as described.

7. In a building construction, in combination, a corrugated sheet, a metal reinforcement, means located in the valleys of said sheet to support the metal reinforcement above the latter, and retaining devices secured in the said valleys and engaging the upper surface of the metal reinforcement, substantially as described.

8. In a building construction, in combination, purlins, corrugated sheets supported by said purlins and having their adjacent ends overlapped above the purlin, a purlin clip engaging said purlin and having a self penetrating rivet extended through the overlapped portions of said sheets, a bridge piece secured to said sheets by said rivet, tension rods supported by said bridge piece, and a layer of concrete laid upon said corrugated sheets and embedding said tension rods and bridge piece, substantially as described.

9. In a building construction, in combination, corrugated members having their adjacent ends overlapped, a support for the overlapping ends of said members, a clip engaging said support and having a substantially flat member resting on said support, and a pointed rivet projecting from the substantially flat member of the clip and through the overlapped corrugated members for riveting the said corrugated members together.

10. In a building construction, in combination, a corrugated sheet, a support upon

which said sheet rests, a metal reinforcement, means secured to said corrugated sheet to support said metal reinforcement away from the corrugated sheet and to secure the same in fixed relation to said corrugated sheet, and means for mechanically securing said corrugated sheet to said support.

In testimony whereof, I have signed my name to this specification in the presence of two subscribing witnesses.

PEREZ M. STEWART.
